[57] **CLAIM**

The ornamental design for a broom with multi-angle handle interconnector, as shown and described.

DESCRIPTION

FIG. 1 is an overall perspective view of a broom with multi-angle handle interconnector showing my new design, the handle interconnector being angled rearwardly; FIG. 2 is a front elevation view of the broom of FIG. 1; FIG. 3 is a rear elevation view thereof; FIG. 4 is a top plan view thereof; and, FIG. 5 is a side elevation view thereof, as viewed from the right of FIG. 2, the opposite side view being a mirror image.
